UNITED STATES PATENT OFFICE.

WALTER N. WILLIS, OF TRAPPE, MARYLAND.

STEAM-ENGINE.

SPECIFICATION forming part of Letters Patent No. 288,684, dated November 20, 1883.

Application filed March 19, 1883. (No model.)

To all whom it may concern:

Be it known that I, WALTER N. WILLIS, of Trappe, county of Talbot, and State of Maryland, have invented an Improvement in Steam-
5 Engines, of which the following is a specification.

My invention has reference to steam-engines; and it consists in a peculiar arrangement of crank and connecting-rod, whereby
10 the crank-pin is caused to travel any desired path that may be described within the circle described by crank-pin when rigidly attached to end of crank-arm, as it is now used, by continually advancing and receding from crank-
15 shaft, as more fully set forth in the following specification and shown in the accompanying drawings, which form part thereof.

Heretofore it has been customary to connect the connecting-rod, through the agency of
20 crank-pin, to the end of the crank, the said crank-pin being thus caused to travel in a circle around the shaft as a center. If we may consider the pressure on the piston uniform, the power exerted at any point in the revolution
25 of the crank will be proportional to a line drawn perpendicular from the center of the crank-pin to the center line of piston extended through center of crank-shaft, the said perpendicular line being the leverage, and this
30 varies from nothing to half the stroke of the engine, and when the leverage of the crank is smallest the movement of the piston is smallest. By this construction the engine is wasteful, and not adapted to turn the crank-shaft
35 at a uniform velocity or uniform power.

The object of my invention is to overcome almost entirely the above objectionable features, by first varying the distance between crank-pin and center of shaft inversely, with
40 variation of leverage in crank as now used; second, by combining the above (first) with the wedge principle involved in pear-shaped cam constructed about connecting-rod, thus tending to insure a uniform power being exerted on crank-shaft to turn it, except at the dead-centers.

In the drawings, Figure 1 is a side elevation of an engine embodying my improvement. Fig. 2 is a sectional plan of same on line $\alpha\alpha$,
50 and Fig. 3 is an elevation of modified means to cause the crank-pin to travel in any desired path that may be traced within a circle.

A is the bed-plate. B is the steam-cylinder. C is the cross-head.

D is crank-shaft, and is supported in bearings E, and carries rigidly secured to its end the crank F, having slot f therein, in which the block or roller G slides.

I is a crank-pin, which pivots the block or roller G to the connecting-rod H, which may be provided with the pear-shaped cam h, arranged about said crank-pin, and in which a roller, K, pivoted by stud J to the end of shaft D, works. As the cross-head reciprocates, the crank-pin I is caused to deviate from a circle, as indicated by dotted lines, and thereby accomplishes the results hereinbefore specified.

In place of using the pear-shaped cam, the crank-pin may be made to travel in a groove of any desired shape, as h', in the face of plate H', as shown in Fig. 3.

This device is equally adapted to machinery other than steam-engines, and the connecting-rod H may be actuated by the shaft, if desired.

I do not limit myself to the exact construction shown, as it may be modified in various ways without departing from my invention.

I am aware of the patents granted to Ruggles, No. 157,765, of 1874, and Rowe, No. 80 102,323, of 1870, and claim nothing therein shown or described.

Having now described my invention, what I claim as new, and desire to secure by Letters Patent, is—

1. A reciprocating connecting-rod, in combination with a crank-pin, a crank, a crank-shaft, and mechanism to cause crank-pin to travel in any desired path that may be traced within a circle, the transverse or longest axis of said path being in line with the connecting-rod when on the dead-centers, substantially as and for the purpose specified.

2. The combination of a connecting-rod, a crank-pin, a crank, a crank-shaft, and cam device, substantially as described, to cause said crank-pin to travel in any desired path that may be traced in a circle, the transverse or longest axis of said path being in line with the connecting-rod when on the dead-centers, substantially as and for the purpose specified.

3. The combination of a connecting-rod, a crank-pin, a crank having a guideway, a crank-shaft, a block or roller pivoted to crank-pin,

and adapted to slide upon said crank, and a cam to cause said crank-pin to move in any desired path that may be traced within a circle, the transverse or longest axis of said path being in line with the connecting-rod when on the dead-centers, substantially as and for the purpose specified.

4. The combination of connecting-rod H, having cam-groove h, crank-pin I, slide G, 10 crank F, guideway f, shaft D, and roller K, substantially as and for the purpose specified.

5. The combination of steam-cylinder B and its piston and piston-rod, cross-head C, connecting-rod H, having cam-groove h, crank-pin 15 I, slide G, crank F, having guideway f, shaft

D, and roller K, substantially as and for the purpose specified.

6. The combination of a connecting-rod, a crank, a crank-pin, a shaft, and a cam so formed as to cause the crank-pin to move in an elliptical path, in which the longest or transverse axis is in line with the dead-center points of the said crank, substantially as and for the purpose specified.

In testimony of which invention I hereunto set my hand.

WALTER N. WILLIS.
